[57] CLAIM

The ornamental design for a three dimensional simulated animal head or similar article, as shown and described.

DESCRIPTION

FIG. 1 is a side view of a three dimensional simulated animal head or similar article embodying a preferred form of our design with the ears, mouth, spheres inside the nose, and body being shown in broken lines for illustrative purposes only;

FIG. 2 is a view of the three dimensional simulated animal head or similar article of FIG. 1 looking generally in the direction of arrows 2—2;

FIG. 3 is a top view of the three dimensional simulated animal head or similar article of FIG. 1;

FIG. 4 is a view looking generally in the direction of arrows 4—4 of FIG. 1;

FIG. 5 is a rear view of the three dimensional simulated animal head or similar article of FIG. 1;

FIGS. 6 and 7 are front and side views of another three dimensional simulated animal head or similar article embodying our design; and

FIGS. 8 and 9 are front and side views of another three dimensional simulated animal head or similar article embodying our design.
